CLAIM

We claim the ornamental design for a barrel tip and spring guide set, as shown and described.

DESCRIPTION

FIG. 1 is a perspective view of a barrel tip and spring guide set, showing the new design;

FIG. 2 is a front elevational view thereof;

FIG. 3 is a rear elevational view thereof; and,

FIG. 4 is a left-side elevational view thereof, a spring guide thereof shown partially broken away for clarity of illustration, the right-side elevational view, top plan view, and bottom plan view thereof all being identical thereto.

The broken lines showing a firearm in FIG. 1 are included for the purpose of illustrating the invention in use, and form no part of the claimed design. The broken lines in FIGS. 2 and 3 depicted environmental matter and form no part of the claimed design.
